APPARATUS FOR GRINDING SERRATED CUTTING BLADES

Harry J. Criner, Davenport, Iowa, assignor of one-half to A. G. Bush, Davenport, Iowa

Application March 4, 1935, Serial No. 9,260

8 Claims. (Cl. 51—72)

My invention relates to new and useful improvements in apparatus for grinding serrated cutting blades.

The objects of my invention are to provide a simple, economical apparatus and process for cutting blades which can be operated at high speed and will not require bending of the blades during the grinding operation and which may be utilized both for grinding new blades from a straight edge 10 or from serrated strips of metal and for sharpening old blades.

I attain these objects by the means illustrated in the accompanying drawings, in which,—

- 15 Figure 1 is an end elevation of my apparatus;
- Figure 2 is a plan view of the same;
- Figure 3 is an enlarged cross-sectional detail of a part of the tilting table, blade support and grinding wheel on the line 3—3 of Figure 2;
- Figure 4 is an enlarged detail showing one of 20 the guiding keys and grooves engaging same in section on the line 4—4 of Figure 1;
- Figure 5 is an enlarged detail of a blade mounted in the blade support and showing a portion of the grinding wheel in section;
- 25 Figure 6 is a plan view of an alternate form of my invention employing a plurality of grinding wheels mounted upon the same shaft; and
- Figure 7 is a front elevation of a portion of Figure 6, but with a portion of the base broken away.
- 30 Similar numerals refer to similar parts throughout the several views.

My apparatus comprises a base, 1, which is preferably made of a heavy flat casting adapted to seat upon a bench, table or other support and 35 may be cast hollow if desired, to reduce weight. At the rear of the base a projecting boss, 2, is formed integral with the base and the boss and base are bored out to receive a post or column, 23. A collar, 24, is slidingly mounted upon the post, 40 23, with a set screw, 24', by which it may be rigidly secured at any desired height upon the column, 23.

A sleeve, 22, is slidingly and revolvably mounted upon the column, 23, above the collar, 24, and is 45 provided with a set screw, 22', by which it may be locked in a given position.

This arrangement of a lockable sleeve combined with a lockable collar, has great advantages in the way of adjustability. In the grinding 50 of blades, it is necessary to adjust the height of the grinding wheel to a nicety relative to the position of the blade. With the arrangement I have shown, if it is desired to lower the grinding wheel say one one-hundredth of an inch, the set screw, 24', upon the collar, 24, may be loosened

and the collar moved downward far enough to insert a feeler gauge one one-hundredth of an inch in thickness between the collar, 24, and the sleeve, 22. The collar may then be pushed upward against the feeler gauge and held in that 5 position while the set screw, 24', is tightened.

The set screw, 22', may then be loosened, the feeler gauge withdrawn and the sleeve, 22, allowed to slide down one one-hundredth of an inch so as to rest upon the collar, 24. The set screw, 22', 10 may then be tightened and the grinding wheel will have been lowered one one-hundredth of an inch.

Similarly, if it is desired to raise the grinding wheel a one-hundredth of an inch, the set screw, 15 22', is loosened, the sleeve, 22, raised slightly and a feeler gauge inserted between the sleeve, 22, and collar, 24. The sleeve may then be lowered to rest upon the feeler gauge and the set screw, 22', tightened. The set screw, 24', may then be 20 loosened, the feeler gauge withdrawn, and the collar, 24, moved upward in contact with the sleeve, 22, and the set screw, 24', again tightened. In this way, the grinding wheel will have been raised one-hundredth of an inch. 25

It is understood, of course, that the contacting surfaces of the collar, 24, and the sleeve, 22, must be ground and polished to a very high degree to permit of such fine adjustments. It is obvious, also, that the use of the collar, 24, with the set screw, 24', combined with the set screw, 22', forms 30 a double locking means to secure the sleeve, 22, at the desired height.

A bracket, 21, is formed integral with the sleeve, 22. A motor, 18, has its foot, 19, bolted to the 35 bracket, 21, with bolts or cap screws 20 and 20'.

The bracket and foot of the motor are made heavy enough to furnish a rigid support for the motor and the motor shaft, 26, is elongated and made heavy enough to support one or more grinding wheels, 15, with the requisite rigidity. 40

When the form of machine illustrated in Figure 6 is used, an additional support, 27, may be mounted upon the table, 5, by set screws, 28', which secure the foot, 28, of the support, 27, 45 to the table, 5, and a bushing, 25, may be mounted within the support, 27, to carry the outer end of the shaft, 26, which may be secured by a nut, 26', threaded upon the outer end of the shaft, 26.

Upon the base, 1, I form lugs, 3, which may 50 be cast integral with the base. Upon the lugs, 3, I mount pivotally, lugs, 6, which are formed integral with the table, 5. The lugs, 6, are secured to the lugs, 3, by a pivot bolt, 8, which permits the table, 5, to tilt, and the nuts, 9, upon the 55

bolts, 8, permit the table, 5, to be locked at any desired angle to the top of the base, 1.

Upon the table, 5, I mount a blade support, 9. The top of the table, 5, and the bottom of the support, 9, are ground to smooth faces so that the support, 9, will slide readily upon the table, 5. The upper face of the support, 9, is beveled at a suitable angle to assist in forming the proper angle or bevel at the cutting edges of the blades. 10 Pins, 10 and 11, are rigidly secured in the support, 9, and spaced apart the necessary distance to accommodate the desired cutting blade, 13, to be ground. In mounting the blade, 13, upon the support, 9, the usual hole in one end of the blade, 13, is placed over the pin, 10, and the hole in the opposite end of the blade, 13, is engaged by a hook, 13', formed upon an extended end of a tension spring, 12, the opposite end of which is hooked over the pin, 11. The spring, 12, is made 20 of sufficient strength and size to apply the necessary strain to the cutting blade while being ground in order to hold it rigidly upon the support, 9.

A plurality of dowel pins, 9', are secured in the support, 9, spaced on opposite sides of the grinding wheel and contact with the rear edge of the blade, 13, being ground so as to prevent displacement thereof rearwardly. The dowel pins, 9', are mounted in suitable openings in the 30 upper face of the support, 9, and a plurality of openings, 9'', may be provided positioned as required for blades of different widths.

In order to properly gauge the support, 9, for the successive serrations to be ground in the 35 blades, 13, I provide a plurality of rectangular grooves, 7', extending laterally in the bottom face thereof. Rectangular keys, 7, are rigidly united to the upper face of the table, 5, extending parallel to the grinding wheels, 15, and to the 40 grooves, 7'.

In order to permit grinding the blades at high speed, it is necessary to provide some means for cooling same and I mount on my machine a waterpipe, 17, with a nozzle formed at the end 45 thereof to project the water to the point of contact between the grinding wheels and the blades. This waterpipe, 17, may be located at a point which will project the water to the point of contact between the grinding wheel and the blade, 50 to the best advantage. I make no claim to any particular position of the waterpipe, 17, and it is obvious that either water or any other suitable cooling fluid may be employed.

In the operation of my machine, the support, 55 9, is slid back upon the table, 5, to the position shown in dotted lines in Figure 2, and the blade placed thereon as already described.

The support is then slid along the top of the table, 5, in position to grind the first serration 60 or scallop and the support is then pushed under the grinding wheel, 15, until it is ready to contact with the wheel. The table, 5, is then adjusted to the desired angle and the motor started. The support, 9, will then be guided by the keys, 7, 65 and can be pushed until the blade, 13, is brought into contact with the grinding wheel and a serration or scallop, 14', ground therein.

When the grinding has been completed for the serration, 14', the support is slid back off 70 the keys, 7, and moved longitudinally one space and then slid forward again upon the keys, 7, to grind the next succeeding scallop or serration, 14'.

The grinding wheels have a curved periphery, 75 curved transversely to cut a scallop or serration,

14', of the desired configuration. The grinding wheels may be made of emery or carborundum or faced with diamond dust or other abrasive so as to stand long wear without requiring redressing, but may be redressed as necessary in the usual wellknown manner.

The blanks for the blades, 13, may be formed with both front and rear edges straight or if desired, the cutting edge may be stamped out into scallops of the desired configuration before 10 being ground.

The points between the scallops will form teeth, 14, and the scallops will be uniformly beveled on both sides by the grinding process. When the blade has been entirely ground upon one side, the 15 support, 9, will be slid back and the blade turned over and replaced, and then ground upon the opposite side in the same manner as above described.

The number of keys, 7, may be varied to suit 20 the requirements of each particular case. In many instances, a single key centrally placed, will be sufficient, but in any event, the keys should be so formed and the number of them so arranged as to insure parallel travel of the support forwardly 25 in its different adjusted positions and to insure uniformity in the scallops or serrations, 14'.

In order to speed up the operation of grinding, a plurality of similar wheels may be mounted upon the shaft, 26, either directly or by mounting them 30 upon a sleeve, 16, which in turn may be rigidly secured upon the shaft, 26.

When two adjacent scallops, 14', are ground at the same time, there is a strong tendency to overheat the intervening tooth, 14, and in using a 35 plurality of grinding wheels, I prefer to space them apart as shown in Figure 6, so as not to grind two adjacent scallops at the same time.

In Figure 6, I have shown the grinding wheels arranged to grind every third scallop and when 40 so arranged, it will only be necessary to use three grinding operations for each side of the blade, but they may be arranged to grind alternate scallops, so that only two grinding operations will be necessary for each side and when driven at a more 45 moderate speed, they may be arranged to cut all of the scallops on one side of the blade at a single grinding operation. The effect of cutting all the scallops at once, will more than make up for the loss of time in slowing down the speed of the 50 grinding wheels.

The upper corner of the support, 9, may be ground sufficient to accommodate the grinding wheel before the blades are placed thereon if desired or it may be ground at the same time that 55 the first blade placed thereon is ground.

It is obvious that various equivalent means of gauging or positioning the support, 9, may be utilized and various modifications may be made in my apparatus without departing from the spirit 60 of my invention and I do not limit my claims to the precise forms shown in the drawings.

It is obvious that this process permits blades to be ground while held in a straight position and without any bending and will obviate the delays 65 incident to placing a blade upon a curved support and in grinding a single serration or scallop at a time.

I claim:

1. A blade grinding machine comprising a fixed 70 base, a column united thereto, a bracket adjustably mounted upon the column and slidably thereon, a collar adjustably mounted upon the column below and adjacent the bracket and slidable on the column, a motor with extended shaft mounted

- upon the bracket, a grinding wheel having a convex periphery keyed to the extended shaft, and means adapted to carry a blade blank to the grinding wheel and rigidly hold same straight while being ground in a succession of uniformly progressive longitudinal positions. 5
2. A blade grinding machine comprising a base, a column united thereto, a bracket adjustably mounted upon the column carrying a motor with 10 extended shaft, a plurality of spaced grinding wheels keyed to the shaft each having a convex periphery, means adapted to support and carry a blade into engagement with the periphery, a table tiltably mounted upon the base, a blade support 15 slidable upon the table, and means coacting between the table and the blade support adapted to guide the support in predetermined successive, uniformly spaced parallel lanes of travel to the grinding wheels. 20
- 20 3. A blade grinding machine comprising a base, a fixed vertical column united thereto, a bracket adjustably mounted upon the column with means permitting fine vertical adjustment thereof and adapted to rigidly secure such bracket in its adjusted position upon the column, a motor mounted 25 upon said bracket with an extended horizontal shaft having a grinding wheel with convex periphery keyed to such shaft, and means supported above the base adapted to rigidly support and to 30 carry a slicing blade into engagement with the periphery of the grinding wheel in a plurality of uniformly spaced successive positions longitudinally of the blade and at a right angle to the plane of rotation of the grinding wheel, and to 35 hold such blades straight while being ground. 4. A blade grinding machine comprising a base, a fixed vertical column united thereto, a bracket adjustably mounted upon the column with means permitting both coarse and fine adjustment thereof 40 and adapted to rigidly secure such bracket in its adjusted position upon the column, a motor mounted upon said bracket with an extended horizontal shaft having a grinding wheel with convex periphery keyed to such shaft, and means supported 45 above the base adapted to support and carry a slicing blade into engagement with the periphery of the grinding wheel in a plurality of uniformly spaced successive horizontal positions and at right angles to the plane of rotation of the 50 grinding wheel and to hold such blade straight while being ground. 5. A blade grinding machine comprising a horizontal base, a fixed vertical column united thereto, a bracket adjustably mounted upon the column 55 with means permitting fine adjustment thereof vertically and adapted to rigidly secure such bracket in its adjusted position upon the column, a motor mounted upon said bracket with an extended horizontal shaft having a grinding wheel with convex periphery keyed to such shaft, a tiltable table pivotally mounted upon the base under and spaced from the grinding wheel, an extended wedge-shaped support manually slidable both longitudinally and transversely upon the table, and means 60 united to the support adapted to secure a blade upon the upper face thereof and to hold said blade under tension in progressive contact with the grinding wheel while being ground. 60

HARRY J. CRINER.
